FIG. 3.

FIG. 2.

D. D. Hunt
INVENTOR
BY Victor J. Evans

L. B. James

WITNESS:

ATTORNEY

UNITED STATES PATENT OFFICE.

DONOVAN DEWEY HUNT, OF LOUISVILLE, KENTUCKY.

HEATER.

Application filed November 19, 1923. Serial No. 675,707.

To all whom it may concern:

Be it known that I, DONOVAN DEWEY HUNT, a citizen of the United States, residing at Louisville, in the county of Jefferson and State of Kentucky, have invented new and useful Improvements in Heaters, of which the following is a specification.

This invention relates to heating apparatus for use in residences or other places and has for its object the provision of a novel device embodying gas burners for heating a blast of air which is conducted to the rooms or other places to be heated.

An important and more specific object is the provision of a device of this character having a peculiar circulation whereby none of the heat will be wasted but all utilized to act upon the coils through which the air passes so as to effect rapid and positive heating.

An additional object is the provision of a device of this character which will be simple and inexpensive in manufacture, highly efficient in use, durable in service and a general improvement in the art.

With the above and other objects and advantages in view the invention consists in the details of construction to be hereinafter more fully described and claimed and illustrated in the accompanying drawings, in which:

Figure 1 is a vertical section through a device constructed in accordance with my invention,

Figure 2 is an enlarged detail view through one of the burners, and

Figure 3 is a detail section illustrating a modification.

Referring more particularly to the drawings I have shown the device as comprising an upstanding preferably cylindrical casing or shell 10 mounted upon legs or other supports 11. Within the top of this shell or casing is a hemispherical distributor 12 from which lead pipes 13 which extend to the various rooms or parts of the building to be heated.

Within the top of the casing 10 is a partition 12^a which extends from the distributor 12 to the wall of the casing 10 to define a chamber 12^c which communicates with the interior of the casing 10 through openings 12^b.

Located within this casing and suitably supported therein is a coil 14 including outer and inner pipe members 15 and 16 respec-

tively, the latter of which connects at its lower end with the outlet 17 of a blower 18 driven in any suitable manner. The upper end of this inner pipe 16 discharges into the bottom of the distributor 12 as shown at 16^a. The air inlet to the blower comprises a coil 19 which has its intake end 20 at the upper portion of the casing and which is arranged between the convolutions of the coil 14, the lower end of this coil 19 leading into the blower casing as shown at 21.

Extending vertically along one side of the casing, exteriorly thereof, is a distributing gas pipe 22 connected with a suitable feed pipe 23. Extending into the casing are burners 24 which are connected with the pipe 22 and which are equipped with the usual mixer 25. The burners 24 are located within the coil 14 between the outer and inner pipes 15 and 16 thereof.

Located near the bottom of the casing are bowl shaped deflectors 26 at which terminate the lower ends of heat return pipes 27 which are curved outwardly away from the upper end of the coil 14 and which communicate with the space between the coil pipes 15 and 16.

In the operation it will be seen that the blower will suck in air through the coil 19 and will discharge air through the pipe 16 of the coil 14. When the burners 24 are in operation it is quite obvious that heat is applied to the space between the pipes 15 and 16 and this will certainly operate to heat the current or blast of air passing through the pipe 16 which air is discharged into the distributor 12 from whence it is conducted through the pipes 13 to the rooms or other places to be heated. The heat ascending through the coil 14 is not wasted but passes through from the upper end of the coil 14 into and downwardly along the pipes 27. The heat issuing from the lower ends of these pipes is deflected upwardly by striking against the deflectors 26 and this heat then circulates through and about all the coils, assisting in heating them. All products of combustion escape through a flue pipe or chimney 28 which communicates with the top of the casing.

In Figures 1 and 2 the members 14, 15, 16 and 24 are all illustrated as being circular in shape. It is apparent that it is not necessary that these elements have this particular configuration and for example I have shown, in Figure 3, corresponding elements

14^a, 15^a, 16^a, and 24^a which are arranged and which operate in the same manner but which are rectangular in cross section.

While I have shown and described the 5 preferred embodiment of my invention it is of course to be understood that I reserve the right to make such changes in the form, construction and arrangement of parts as will not depart from the spirit of the invention or the scope of the subjoined claims.

Having thus described my invention I 10 claim:

1. A heating device of the character described comprising a casing, a plurality of 15 distributor pipes leading from the top thereof, a coil located within the casing and including two air pipes one within the other, a blower having its outlet connected with one 20 end of the inner air pipe, the upper end of said inner air pipe having communication with said distributing pipes, and an air inlet for the blower and burners located between the air pipes for heating the same.

2. A heating device of the character described comprising a casing, a plurality of 25 distributor pipes leading from the top thereof, a coil located within the casing and including outer and inner air pipes, a blower having its outlet connected with one end of 30 the inner pipe, the upper end of said inner pipe having communication with said distributing pipes, and an air inlet for the blower and burners located within the coil for heating the same, the burners being in 35 the space between the inner and outer air pipes and being fed from a common source of supply.

3. A heating device of the character described comprising a casing, a plurality of

distributor pipes leading from the top thereof, a coil located within the casing and including two air pipes one within the other, a blower having its outlet connected with one end of the inner air pipe, the upper end of said inner pipe having communication 40 with said distributing pipes, an air inlet for the blower and burners located between the air pipes for heating the same, heat return pipes leading from the upper end of the space between the inner and outer air pipes 45 of the coil and extending toward the bottom of the casing, and deflectors near the bottom of the casing above which said return pipes terminate.

4. A device of the character described 50 comprising a casing provided at its top with an outlet flue, a hollow distributor within the top of the casing, distributor pipes leading from said distributor, a coil mounted within the casing and formed of inner 55 and outer pipes arranged in spaced relation, a blower connected with the lower end of the inner pipe, the upper end of the inner pipe being connected with said distributor, gaseous fuel burners located between the 60 outer and inner pipes of the coil, downwardly extending pipes communicating with the space between said outer and inner pipes, deflecting bowls within the bottom of the casing and above which said downwardly extending pipes terminate, and an air inlet pipe formed as a coil located between the 65 convolutions of the first named coil and having its upper end communicating with the atmosphere and its lower end leading into 70 the blower casing.

In testimony whereof I affix my signature.
DONOVAN DEWEY HUNT.
